ELECTRON DISCHARGE TUBE WATER JACKET

Clinton H. Suydam, Verona, N. J., assignor to
Federal Telegraph Company, Newark, N. J., a
corporation of California

Application December 31, 1937, Serial No. 182,647

4 Claims. (Cl. 250—27.5)

This invention relates to water jackets for vacuum tubes and pertains more particularly to demountable water jackets which may be quickly adjusted for the insertion or removal of a vacuum tube.

It is an object of my invention to provide a jacket structure whereby a vacuum tube anode having an annular shoulder or ring thereon may be quickly clamped into position without the aid of complicated tools.

In accordance with my invention the end of the water jacket adjacent the metal to glass seal of a vacuum tube or electron discharge device is provided with a plurality of posts serving to support a screw threaded ring adapted for engagement with a holding collar which serves to retain the vacuum tube in proper position relative to the jacket. The threaded ring may be a complete circle or composed of segments, each of which is supported by a post. The spacing between these posts is sufficiently wide to permit the operator to adjust the split ring elements cooperating with the retaining collar and adapted to hold the tube in position. If desired and as shown in the drawing the spacing between the posts may be made wide enough to permit of the complete removal or insertion of the split ring elements without necessitating the removal of the vacuum tube from the water jacket. Alternatively the split ring may be hinged at one side, in which event the wide spacing between the posts leaves the sides of the split ring freely exposed so that the ring may be opened and moved out of position preparatory to the removal of the vacuum tube from the jacket.

The above mentioned and further objects and advantages of my invention and the manner of attaining them will be more fully explained in the following description taken in conjunction with the accompanying drawing.

In the drawing,

Fig. 1 is a side elevation view partly in section of a jacket structure embodying my invention.

Fig. 2 is an end view taken along section line 2—2 of Fig. 1.

Fig. 3 is a plan view showing a modified form of split ring having a hinge therein, and

Fig. 4 is a sectional view taken along section line 4—4 of Fig. 3.

Referring more particularly to the drawing, reference numeral 1 indicates generally a water jacket or casing having two connection nipples 3 and 4 and a water inlet channel 5. Water is intended to enter through a nipple 3, pass through the passage 5, circulate around the metal anode

of an electron discharge device (not shown) which the jacket holds in position and then pass out through the water outlet nipple 4. The right hand end of the jacket 1, as illustrated in Fig. 1, has attached thereto by screws 18 two posts 6 and 7, which in turn support a threaded ring 8 preferably formed integrally therewith. The ring 8 has screw threaded therethrough a pressure collar 9 having an inwardly sloping annular portion 10 terminating in a pressure face 11 which engages with the two halves or sections 12 and 13 of a split ring indicated generally by reference numeral 14. This split ring has a recess 15 in the surface thereof adjacent the pressure face 11 of collar 9 with which the pressure face engages, with the result that the two halves of the ring are held together and are prevented from spreading apart during the tightening of the collar. The other side of the split ring is chamfered slightly at 16 so as to permit free movement thereof toward the main body of the jacket 1, the portion of the jacket adjacent to the ring 14 being provided with a recess or seat 17 adapted to receive a shoulder or ring fixed to or integral with the tubular metal anode of an electron discharge device.

Reference numeral 19 indicates knurled handles attached to the halves 12 and 13 of split ring 14, by means of which these halves may be inserted and removed as desired.

In operation the collar 9 is unscrewed far enough to permit the removal of the two halves 12 and 13 of split ring 14. The tubular anode of an electron discharge device is thrust through the opening in the collar 9 and moved into the opening in jacket 1 far enough to bring the ring or shoulder carried by the anode into the recess or seat 17 of the jacket, which seat it is adapted substantially to fill. At the same time gaskets may be provided for one or both sides of the ring or shoulder of the anode so as to insure a water tight joint with the seat 17.

The two halves or sections 12 and 13 of split ring 14 are then placed in position between the pressure face 11 of the collar 9 and the opposite face of the anode shoulder, and the collar 9 is screwed into position so as to force the split ring 14 tightly against the shoulder of the discharge device. The resulting pressure clamps the anode shoulder tightly in the seat 17 and forms a water tight joint.

As shown on the drawing, the spacing between the posts 6 and 7 is made wide enough to permit the direct removal of the sections 12 and 13 of split ring 14 and the insertion thereof without

special tools, this wide opening also serving to permit ready access for the adjustment of gaskets or other sealing parts during the tightening operation.

5 Figs. 3 and 4 show an alternative form of split ring wherein a hinge 20 is provided at one side thereof. When this type of ring is used in place of the split ring shown in Figs. 1 and 2, the spacing between the posts 6 and 7 need not be great enough to permit the complete removal of the hinged ring from the structure by passage thereof between the posts, since the removal of a vacuum tube from the jacket can still be easily effected because of the ready accessibility of the ring for opening and closing thereof, and for the adjustment of any gaskets.

10 In the above description two posts only have been mentioned but more, e. g. three, could be used if desired, so long as the space between the 20 adjacent posts is large enough to accomplish the desired purpose of permitting ready access to or removal of the split ring. Likewise, the split ring may be made in more than two sections if desired.

15 While I have described particular embodiments 25 of my invention for the purpose of illustration, it should be understood that various modifications and adaptations thereof may be made within the spirit of the invention as set forth in the appended claims.

20 I claim:

1. A water jacket assembly for an electron discharge device comprising a casing, a screw threaded clamping collar, a split ring positioned coaxially with said collar and adapted to engage

therewith and transmit clamping pressure from said collar to a portion of said discharge device, and a plurality of spaced posts extending from said casing and having means for engaging the screw threads of said clamping collar, the spacing between said posts being great enough to expose said split ring substantially entirely to view so that the seating thereof during the adjustment of said collar may be observed and ready access may be had directly to said ring. 10

5 15 20 25 30 2. A structure in accordance with claim 1 wherein said split ring is made of a plurality of separable sections and the spaces between said posts are great enough to permit the direct removal of said sections from said casing through said spaces.

3. A structure in accordance with claim 1 wherein said split ring comprises a plurality of sections hinged together.

4. A water jacket assembly for an electron discharge device having a shouldered anode, comprising a casing having a seat adapted to receive the shoulder of said anode, a screw threaded clamping collar for pressing said shoulder against said seat, a split ring positioned between said collar and said shoulder, and a plurality of spaced posts extending from said casing and having means for engaging the screw threads of said clamping collar, the spacing between said posts being great enough to expose said split ring and permit direct removal thereof from said casing through the space between said posts.

CLINTON H. SUYDAM.
